UNITED STATES PATENT OFFICE.

OWEN JAMES, OF FALL RIVER, MASSACHUSETTS.

SYRINGE.

1,072,467.

Specification of Letters Patent.

Patented Sept. 9, 1913.

Application filed May 4, 1912. Serial No. 695,117.

To all whom it may concern:

Be it known that I, OWEN JAMES, a citizen of the United States, residing at Fall River, in the county of Bristol and State 5 of Massachusetts, have invented new and useful Improvements in Syringes, of which the following is a specification.

This invention relates to syringes and more particularly to nozzles therefor.

10 One of the principal objects of the invention is to provide a nozzle which may be readily attached to any type of fountain syringe now on the market. In the treatment of diseases by clyster, it is found that 15 an injection can not be properly made owing to the spasmodic action of the anal sphincter, and it is the object of this invention not only to provide a simple and efficient attachment but to also produce one 20 which will give sufficient rectal support when used in sitting posture.

Further objects of this invention will appear as the following specific description is read in connection with the accompanying 25 drawing, which forms a part of this application, and in which:—

Figure 1 is a side elevation of the device. Fig. 2 is a sectional view on the line 2—2 of Fig. 1. Fig. 3 is a similar view showing 30 the straight tube connection.

Referring more particularly to the drawing, 1 represents the body of the device which is of substantial bell, or inverted, cup shape formation and is provided with a 35 notch 2 in its lower edge to receive or promote the passage of the rubber tube 3 which extends from the back or fountain, not shown. Projecting upwardly from the bell-shaped body and merging smoothly into 40 the same is a nozzle 4 provided with the

usual spray openings 5 and with the central bore 6 communicating therewith. Depending from the upper portion of the bell or projecting thereinto is a nipple 7 having its central bore 8 communicating with the 45 bore 6 in the nozzle. This nipple is adapted to receive the end of the hose in the ordinary manner.

In Fig. 3, the hose is shown removed from the notch 2 and projected directly in line 50 with the nipple and nozzle. This figure is supplied simply to show that the device may be used in the ordinary manner of syringe nipples without resting the same upon a 55 support.

In Fig. 2, the bell-shaped body is shown as provided with a curved partition 8 which is adapted to prevent the tube from kinking where it emerges from the body.

What is claimed is:—

1. A syringe attachment comprising a nozzle, a bell-shaped body secured thereto and merging smoothly into the nozzle, and a nipple extending into the bell-shaped body, 65 said bell-shaped body having a tube receiving notch in its lower edge.

2. A syringe attachment comprising a nozzle, a bell-shaped body secured thereto and merging smoothly into the nozzle, a 70 nipple extending into the bell-shaped body, said bell-shaped body having a tube receiving notch in its lower edge and a curved partition in said body to prevent kinking of the tube.

In testimony whereof I affix my signature in presence of two witnesses.

OWEN JAMES,
